C. MUNZNER

GAS BURNER

Filed Aug. 2, 1923

Inventor

Charles Mangner
A. S. Patterson & Son

Attorney

UNITED STATES PATENT OFFICE.

CHARLES MUNZNER, OF CHICAGO, ILLINOIS, ASSIGNOR TO AMERICAN STOVE COMPANY, OF ST. LOUIS, MISSOURI, A CORPORATION OF NEW JERSEY.

GAS BURNER.

Application filed August 2, 1923. Serial No. 655,229.

To all whom it may concern:

Be it known that I, CHARLES MUNZNER, a citizen of the United States, residing at Chicago, in the county of Cook and State 5 of Illinois, have invented certain new and useful Improvements in Gas Burners, of which the following is a specification, reference being had therein to the accompanying drawing.

10 This invention relates to improvements in gas burners and more particularly to a gas burner adapted for use as a pilot light. Most burners which are used as pilot lights burn a yellow flame for the reason that 15 there is no pre-mixture of air with the gas before it reaches the burner.

The object of my invention is to provide a gas burner which will produce an annular flame.

20 Another object of my invention is to provide a gas burner which will produce an annular flame the size of which can be quickly and readily adjusted or varied.

25 A further object of my invention is to provide a gas burner wherein the flow of gas is readily and easily controlled in such a way that there is a marked improvement in the manner in which the flame holds on.

30 Another and further object of my invention is to provide a gas burner which is very simple of construction, cheap of manufacture and highly efficient in operation.

Other and further objects and improved results of my invention will appear in the 35 following description and accompanying drawings.

In the drawings:—

Figure 1 is a perspective view of my improved burner.

40 Figure 2 is a vertical sectional view of the burner shown in Figure 1.

Referring now to the drawings in which like parts are designated by similar reference numerals throughout the description—

45 One (1) designates a gas supply conduit which is in screw-threaded engagement at 2 with a hollow cylindrical open-ended shell or housing 3 of my burner.

50 The upper end of the housing 3 is provided with a smooth beveled edge 4 past which the gas escapes to be burned. The amount of gas which escapes and the size of the flame is controlled by an adjusting plug 5 which is in screw-threaded engage-

ment as at 6 with the walls of the opening 55 7 of the shell.

The adjusting plug 5 is provided with a centrally located gas conduit 8 which terminates at its upper end with a series of radially disposed cross conduits or gas-outlets 9 through which the gas escapes into a distributing chamber 10 to pass ultimately past the beveled edge 4 before mentioned.

The plug 5 is provided with an enlarged head 11 having a tapered or beveled bottom or under-side 12. The bevel 12 of the plug is in approximately a parallel plane with the beveled edge 4 of the housing 3 but separated therefrom. The head 11 of the plug is further provided with a slot or groove 13 adapted to be engaged by a screw-driver or some similar tool.

From the foregoing description the operation of the burner should now be quite clear. The gas enters the housing 3 through the conduit 1, passing through the opening or chamber 7 upwardly through the adjusting plug main conduit 8 and thence outwardly through the cross conduits 9 into the distributing chamber 10. From the distributing chamber the gas passes upwardly and outwardly between the beveled edges of the housing and adjusting plug to be burned.

Due to the fact that the housing and plug 85 are cylindrical the flame produced is an annular one and the size of the flame can be readily and easily adjusted by screwing the adjusting plug 5 upwardly or downwardly within the housing. The movement of the 90 adjusting plug 5 controls the amount of gas which escapes to be burned rather than controlling the flame by choking it. The adjusting plug 5 is not a flame deflection 95 but is rather in the nature of a gas check. As the plug is screwed upwardly and downwardly the opening between the beveled faces 12 of the plug and the beveled edge 4 of the housing is reduced and the flame is therefore naturally diminished.

100 For the purpose of convenience the outer lower end of the housing 3 is provided with a series of square surfaces 14 to form a nut so that the housing can be tightened upon the conduit by means of a wrench.

105 It will be readily understood that if it were desired the housing and plug could be made any shape other than cylindrical

to meet various requirements and conditions without departing from the spirit of my invention.

Having thus described my invention what 5 I desire to protect and secure by Letters Patent is:—

A gas burner comprising a housing having an intermediate internal screw-threaded portion, its upper end beveled outwardly, 10 an interior member having its lower end made hollow and provided with an intermediate reduced portion, its upper solid end flared outwardly to correspond with the

bevel of the outer extremity of the housing, laterally extending openings formed 15 through the intermediate reduced portion and the enlarged lower end screw-threaded to fit the intermediate screw-threads of the housing, whereby a chamber is formed between the said intermediate reduced portion and the housing, and the enlarged head is adjustable, for the purpose described.

In testimony whereof I hereunto affix my signature.

CHARLES MUNZNER.
